GRANVILLE F. THAYER, OF PROVIDENCE, RHODE ISLAND, ASSIGNOR TO M AND T
BUTTON COMPANY, OF BOSTON, MASSACHUSETTS, A CORPORATION OF MASSA-
CHUSETTS.

SHOE-BUTTON.

1,256,614.

Specification of Letters Patent. Patented Feb. 19, 1918.

Application filed August 25, 1917. Serial No. 188,197.

To all whom it may concern:

Be it known that I, GRANVILLE F. THAYER, a citizen of the United States, residing at Providence, in the county of Providence,

5 State of Rhode Island, have invented certain new and useful Improvements in Shoe-Buttons, of which the following is a specification.

10 My invention relates to shoe-buttons and consists of improvements in the form and structure thereof. The object of my improvement is to provide a button which may be more readily and easily released in unbuttoning it, without unduly stretching, 15 straining or tearing the edges of the button-hole.

In carrying out the improvement I provide the head of the button with sloping sides, giving the under portion of its body 20 substantially the shape of an inverted, truncated cone which acts with a wedging effect in passing it through the button-hole.

This novel and improved form and structure of the button is described in detail in 25 the following specification, illustrated by the accompanying drawings, in which like reference characters designate like parts. In the drawings:—

Figure 1 is an enlarged, side view of my 30 improved button;

Fig. 2, a sectional view taken on the vertical axis of the head, showing the method of securing the eye thereto and illustrating the manner in which the button sets in the 35 button-hole; and

Fig. 3, an inverted, plan view of the button.

Referring to the drawings, my improved 40 shoe-button B as here shown comprises a head or "bean" H molded from paper, fiber or similar pulp-like material, combined with a wire shank or fastening-eye S bent into the form of a U-shaped loop and joined to the head at its base. Heretofore, the usual 45 style of button employed for fastening shoes has been constructed with a head or bean of substantially elliptical shape in cross-section having a relatively broad, flaring base from which projects a ring-shaped eye 50 formed with a narrowed neck or shank at its point of joinder with the head. With

this latter type of button the button-hole fits closely around the reduced neck of the eye with its margin bearing against the relatively flat, under side of the bean or head. 55 In unbuttoning the shoe its flap is grasped at the edge and pulled outwardly to slide the button-hole over the periphery of the button. Now, when the button is made with a head having a broad, flaring base, as above 60 described, the margin of the button-hole cannot be easily spread out around its sides and released therefrom. That is to say, this shape of head tends to resist the opening of the button-hole around the button and 65 hence considerable force must be exerted to unbutton the flap, while the button-hole is liable to be stretched, strained and torn at its edges. After the button-hole becomes torn or frayed it will not hold the button 70 properly, and besides this presents an unsightly appearance which detracts from the neatness of the shoe.

To avoid these disadvantages of the ordinary shoe-button I propose constructing my 75 improved type with a head having sloping sides, or, more particularly, with its underbody taking the form of a truncated cone. In this way I adapt the under part of the head to serve substantially as a wedge, 80 whereby when it is unbuttoned it acts to spread the sides of the button-hole apart to ease the marginal edges thereof over the outer periphery of the button. As shown particularly in Fig. 1, the head H of the 85 button is shaped with a crowned top t, having a considerable degree of convexity to give it an ornamental appearance, while below the crown the sides c slope or taper inwardly at a sharp angle to form the inverted cone-shaped underbody C. The sides of the cone C are preferably straight, as shown in Fig. 2, although if desired they might be slightly rounded or convexed, but not to any considerable extent as this would 90 tend to flatten the whole base of the head and thereby defeat the purpose at which the improvement is aimed. The sides c of the cone C merge into the crowned top t at the periphery p of the head H with a 95 sweep or curve of relatively short radius, while at the bottom of the head H the vertex 100

of the cone C is truncated to form the flat facet or base b.

Projecting from the base b of the head H is the eye S employed for fastening the button to the shoe and, as before stated, this takes the form of a U-shaped loop bent up from a suitable length of wire. The legs l, l of the loop or eye S are either driven into the head H or embedded in the material when it is molded, and their ends are preferably clenched or riveted over at the top as shown at s, s, Fig. 2. It is to be particularly noted that the opposite sides of the eye S are straight and parallel and that they join the head at points contiguous to the marginal edge of the flat base b, see Fig. 3. In other words, the extreme width across the eye S, from the outside of one leg l to the outside of the other leg l, is exactly equal to the diameter of the rim of the base b.

This feature of arrangement is particularly important as providing that when the eye S is seated in the button-hole f of the flap F, as shown in Fig. 2, the outer end e of the button-hole will lie outside of the rim of the base b. That is to say, the circular end-portion of the button-hole is maintained away from the edge of the flattened base b so that its margin will not meet with any obstruction in passing up over the tapering sides of the head H. Thus, it will be seen that when the outer edge of the flap F is pulled upwardly the sloping sides e of the head H will act against the marginal edges of the button-hole to spread them apart and ease them over the outer periphery p of the button.

The parallel arrangement of the legs l, l of the staple or eye S further provides for greater facility in driving it into the head H. Heretofore it has been the usual custom to cross the legs of the staple where they enter the base of the button and to drive them in at an angle with their ends diverging. It is obvious that if the two ends of the staple are driven into the head of the button at an inclination they will enlarge the openings where they enter so that the joint has an unfinished appearance. On the other hand, with the present form of eye or staple the legs are driven into the base of the button in a right-line or perpendicular thereto so that the holes which they enter are not enlarged or distorted and hence the joint has a much neater and more finished appearance.

It will be observed from the foregoing that the particular feature of improvement of the present invention resides in shaping the lower body of the button-head H with tapering sides and in joining the loop or staple S thereto with its legs entering the flat base contiguous to its circumferential rim. As is well known, the button-hole is usually formed with a narrow slit and an enlarged, circular opening at its outer end with the marginal

edges reinforced by stitching. The enlarged end of the button-hole is of sufficient width to receive the base b of the button with a slight clearance, and its outer end bears against one side of the eye S when the flap F is buttoned thereover as shown in Fig. 2. Now, when it is desired to unbutton the flap F the circular opening at the end of the button-hole rides easily over the rim of the base b and a very slight pull will serve to spread it out around the head H as the lower, conical portion thereof acts to wedge its edges apart. In this way the flap F may be readily unbuttoned without straining, stretching or tearing the button-holes and therefore the shoe-upper does not become worn or unsightly in appearance.

I am aware that it has before been proposed to provide a shoe-button with a projecting neck or collar on its under side which enters between the sides of the button-hole to prevent the eye from wearing its edges. This form of button has not been entirely practical in use, however, since its neck is so slight that it rides out of the button-hole and the edge therefore bears against the eye when the flap is under tension. Furthermore, as the neck merges into the sides of the button-head with a relatively sharp, ogee curve a shoulder or ledge is formed which presents an obstruction to the sides of the button-hole when the flap is unbuttoned and therefore prevents a free and easy release of the button. In my present improvement there are no shoulders or ledges on the under side of the button to catch the edges of the button-hole and hence the button will slide easily therethrough as its tapering sides act to spread the opening apart.

What I claim is:—

1. An improved shoe-button comprising a head shaped with a convexly crowned top and substantially straight sloping sides tapering inwardly from the periphery of the head and terminating in a flat circular base, and a U-shaped eye formed with parallel legs inserted in the base of the head with its sides tangent to the circumferential rim thereof.

2. An improved shoe-button comprising a head shaped with a convexly crowned top and substantially straight sloping sides tapering inwardly from the periphery of the head, with the under part of the button formed substantially as an inverted truncated cone, and a wire eye joined to the head with its sides contiguous to the edge of its flat circular base.

3. An improved shoe-button comprising a head shaped with a rounded top and substantially flat inwardly tapering sides forming a conical underbody terminating in a flat circular base, and a U-shaped wire staple having straight parallel legs driven into the base at its rim in perpendicular relation

thereto with the ends of the staple clenched over the top of the head to secure it therein.

4. An improved shoe-button comprising a head shaped with a convexly crowned top and flat sloping sides merging into the top at the periphery of the head and tapering inwardly therefrom to form an inverted

cone, truncated at its vertex to provide a flat circular base, and a wire loop joined to the head with its sides tangent to the circumferential rim thereof. 10

In testimony whereof I affix my signature.

GRANVILLE F. THAYER.
